UNITED STATES PATENT OFFICE

KINJIRO OKABE, OF SENDAI, JAPAN

VACUUM TUBE

Application filed May 11, 1926, Serial No. 108,406, and in Japan March 5, 1926.

My invention relates to vacuum tubes and more particularly to types of vacuum tubes having multiple electrodes to be used as amplifiers or oscillators and the like.

5 The object of my invention is to provide an improved vacuum tube of superior character whereby the internal resistance can be remarkably reduced resulting in a great increase of anode current and also mutual conductance which is the ratio of the amplification constant divided by the internal resistance.

An ordinary vacuum tube of three electrodes comprises a plate, a filament and a grid, and these elements are usually connected between the terminals of batteries and also to an oscillating circuit consisting of inductance and capacity though not necessarily limited thereto. Such triode vacuum tubes 15 are known as a "pliotron". My invention has reference to such kinds of vacuum tubes and is characterized by the feature that an auxiliary anode is provided and also the plates are specially arranged so that electrons may pass freely between them. In other words, according to my invention the secondary emission of electrons is utilized in a particular way, and the vacuum tube embodying my invention may be known as 20 an excited vacuum tube which emits secondary electrons excited by primary electrons, or it may also be termed as a secondary electron vacuum tube. There is a certain class of vacuum tubes known as "dynatrons" which 25 also utilizes the secondary emission of electrons but they differ from that of my invention both in principle and operation. The excited vacuum tube so called rather resembles the ordinary triode, but the mutual conductance of the excited vacuum tube is a few times larger than that of the triode if compared under the same conditions. I have obtained satisfactory results in successfully operating the excited vacuum tube as an oscillator or an amplifier. The mutual conductance is the most important factor determining the superiority of a vacuum tube and if it is larger it gives remarkable improvement in the character of a vacuum tube.

30 For a better understanding of my invention, reference is had to the following description taken in connection with the accompanying drawing, in which Fig. 1 diagrammatically illustrates a four element vacuum tube embodying my invention; Fig. 2 is a side view; Fig. 3 is a side view of a modified form having a cylindrical anode; Figs. 4 and 5 illustrate these vacuum tubes in perspective views, and Fig. 6 is a diagrammatic elevational view of a tube embodying the invention.

35 The novel features and combinations which I believe to be characteristic of my invention are pointed out with particularity in the appended claim.

40 Referring now, more particularly to the drawings, especially Figs. 1 and 2, the vacuum tube embodying my invention comprises essentially a filament F, a grid G, a plate P and a secondary plate or auxiliary anode S. A suitable number of these elements may be adopted and it will be evident from these figures that a number of plates P which constitute anodes of this vacuum tube corresponding to the anode of an ordinary triode 45 are arranged in spaced relation with each other and extremely near to the auxiliary anode S and each of these anodes P is located so that its vane tip subtends a certain angle θ against the common normal between the filament and auxiliary anode as seen more clearly from Fig. 1. This is the most essential feature of my invention. In this case I have used plane anodes and found that a 50 better result can be obtained by making the auxiliary anode S of aluminium for moderate size but it should be made of some other metal in a larger power unit as aluminium melts away in such cases. I have found that the emission of the secondary electrons can 55 be greatly increased by coating the surface of such auxiliary anode with nickel oxide and tungsten oxide. In carrying this into effect I have found it most convenient to use grids G and plates P made of nickel and a tungsten filament F, then evacuate the tube and send in a little air or oxygen and allow the electric current to pass through them, then the oxides formed will naturally adhere to the auxiliary anode S to a high degree,

60 65 70 75 80 85 90 95 100

though some oxide attached to the plate will give a better effect. In the modified form of the excited vacuum tube so called shown in Figs. 3 and 5 the auxiliary anode S is made in a cylindrical form and the plates P are arranged along its inner periphery and the grid G is located around the filament F which is placed at the centre of the tube. The plates P, should essentially be placed extremely near the auxiliary anode S and each vane may be arranged either radially or at a small angle θ with the radius if desired. In this case the radius means a common normal line between the circumference of S and the axis of F.

15 The principle of operation of the vacuum tube embodying my invention as arranged and constructed as above is as follows:

Electrons from the filament F are put in motion by the electric field between F and P and all of the thermo-electrons as accelerated by the anode P will pass through the space between the anodes P until they impinge on the auxiliary anode S, and then the secondary electrons are emitted from this anode S. In order that all of the emitted secondary electrons can be absorbed by the plates P, the distance between P and S is made extremely small.

30 The number of the secondary electrons is very much more than the number of primary electrons. These secondary electrons are liable to be attracted further to the positive anode P. Thus the number of electrons flowing to the anode P will be a few times greater than that of the primary electrons issued from F. As the whole electron current flowing through P can be controlled by the grid G, the vacuum tube or special triode according to the present invention has a very large mutual conductance.

As it is evident from the foregoing the vacuum tube according to my invention is characterized by the feature that the plate current or anode current is remarkably increased to about 2 to 3 times and less heat is generated in the vacuum tube. This latter feature is due to the fact that the size of filament can be greatly reduced according to my invention as compared with that necessary for an ordinary triode since the plate current can be greatly increased even with a smaller filament which is the source of primary electrons, thereby reducing the heat generation of the filament. Moreover the auxiliary anode S is less heated because all of the primary electrons which impinge on the auxiliary anode S are not dissipated as heat energy, but a considerable energy is spent for emitting secondary electrons, so aluminium plates can be used in moderate size as already stated. As the thermo-electron passes in a direction parallel to the surface of the plate P the operation of the vacuum tube according to my invention will be somewhat varied if

magnetic field is applied to it, but it rather belongs to the other special application of my invention.

For a better understanding of my invention I will briefly explain the principal difference between the known type of vacuum tubes such as "dynatron" and the super-triode according to my invention. Since in the dynatron the current passing through the electrode S is utilized it has the characteristic of negative resistance or of falling character, while in the present invention the current through the plates is utilized and therefore has the nature of positive resistance as in the case of ordinary triodes. In dynatrons suitable forms of electrodes corresponding to the electrode P are specified and limited to such forms as a spiral wire, a perforated cylinder or a squirrel cage, all of which are quite different from that of my invention. It will be evident from the foregoing that my invention is clearly different from so-called dynatron both in principle and operation as well as in its construction without any further description.

90 In accordance with the provisions of the patent statutes I have described the principle of operation of my invention together with the apparatus which I now consider to represent the best embodiment thereof but I would have it understood that the apparatus shown is only illustrative and that the invention may be carried out by other means.

95 What I claim as new and desire to secure by Letters Patent of the United States, is:

100 A vacuum tube comprising a filament, a control grid spacedly disposed on each side of said filament, main anodes spacedly disposed adjacent the outward sides of said grid and aluminum auxiliary anodes coated with nickel oxide and tungsten oxide spacedly disposed adjacent the outward sides of said main anodes whereby the variation in the anode voltage directly depends upon the primary electron current from the filament and the current in the main anode.

105 In witness whereof, I have hereunto set my hand this twenty-second day of March, 1926.

KINJIRO OKABE.
